UNITED STATES PATENT OFFICE.

THOMAS H. GORDON AND EDWARD N. DOW, OF HUDSON, NEW YORK.

IMPROVEMENT IN BOOT AND SHOE SHANKS.

Specification forming part of Letters Patent No. **132,719**, dated November 5, 1872.

To all whom it may concern:

Be it known that we, THOMAS H. GORDON and EDWARD N. DOW, of Hudson, in the county of Columbia and State of New York, have invented certain new and useful Improvements in the Soles of Boots and Shoes; and we do hereby declare that the following is a full, clear, and exact description thereof, that will enable others skilled in the art to which it appertains to make and use the same, reference being had to the accompanying drawing and to the letters of reference marked thereon which form a part of this specification.

The nature of our invention consists in the construction and arrangement of a shank for boots and shoes, as will be hereinafter more fully set forth.

In order to enable others skilled in the art to which our invention appertains to make and use the same, we will now proceed to describe its construction and operation, referring to the annexed drawing, in which—

Figure 1 is a bottom view, and Fig. 2 is a side view, of our invention.

Our shank consists of three pieces—a piece of leather, A, called the preserver, and two springs, B and C. The spring C is a light narrow spring, riveted at its ends to the spring B. The spring B is made heavier and of the form shown in Fig. 1. It is fastened on the under

side of the preserver A by means of clamps *a*, one at each end. At the heel of the spring B should be a notch or hole, *b*, as a tack-guide, that the shank may be placed in its position. It is placed between the insole and sole of the boot or shoe where the filling is now usually inserted.

With this shank there is no filling needed, thus saving time in the manufacture of the boot or shoe; and it also gives greater ease to the wearer, keeping the boot or shoe always up in the hollow of the foot and forming a spring-support for the same.

Having thus fully described our invention, what we claim as new, and desire to secure by Letters Patent, is—

The within-described shank for boots and shoes, consisting of the preserver A and springs B and C, constructed and arranged substantially as shown and described, and for the purposes set forth.

In testimony that we claim the foregoing we have hereunto set our hands this 20th day of September, 1872.

THOMAS H. GORDON.
EDWARD N. DOW.
